CARTON

William P. Frankenstein, Cincinnati, Ohio

Application May 23, 1947, Serial No. 749,955

22 Claims. (Cl. 229—34)

1

This invention relates to improvements in cartons or boxes and particularly to cartons or boxes of the knocked-down type.

Foldable boxes of the knocked-down type are old and well known. The present invention being directed to improvements therein when formed particularly of a single blank and the cartons or boxes disclosed in this application, by way of illustration of the invention, are improvements on the box or carton disclosed in applicant's Patent Re. 21,158. The cartons or boxes of the present invention are primarily intended for producing insulated packages for insulating the contents thereof against the atmosphere and will find their uses, amongst others, as a cigar humidor, frozen food package or container, a package insulated against shock while in shipment and containing frangible articles and a package for shipping and displaying a plurality of articles of contours resulting in cross sections that are not uniform throughout their lengths or heights.

It is, therefore, the principal object of the present invention to provide an insulated package, the carton of which is formed of a single blank of cardboard or paper material so designed as to readily accommodate insulating filling or packing material.

Another object of the present invention is to provide a carton or box of the knock down style formed from a single blank of card or paper board material that has spaced apart walls to receive insulation that cooperates with an insulated bottom.

It is also an object of this invention to provide a carton or box to accomplish the objects set forth in the preceding paragraph and in which the blank provides a lid or cover integral therewith to insulate the normally open upper end of the box or carton.

A further object of the present invention is the provision of a carton or box of the knock down type formed of a single blank of card or paper board material having walls capable of insulating the interior from the surroundings together with a lid or cover separable from or integral with the box or carton likewise capable of insulating the contents of the box or carton from its surroundings.

A still further object of the present invention is the provision of a box or carton for accomplishing the above objects that is simple of construction, erectable from a flat or knocked-down condition to a usable condition and economical to manufacture and acquire consistent with the purposes to be accomplished thereby.

Other objects and advantages of the present

invention should be readily apparent by reference to the following specification considered in conjunction with the accompanying drawings forming a part thereof and it is to be understood that any modifications may be made in the exact structural details there shown and described, within the scope of the appended claims without departing from or exceeding the spirit of the invention.

2

30 In the drawings:

Fig. 1 is an extended plan view of a blank erectable into a carton illustrating one form of the invention.

Fig. 2 is a transverse sectional view of the blank of Fig. 1 as shipped to the user.

Fig. 3 is a perspective view of the erected carton of Fig. 1 with one end thereof open for more clearly illustrating the invention.

Fig. 4 is a longitudinal sectional view of the carton as seen from line 4—4 on Fig. 3.

Fig. 5 is an extended plan view of a half blank showing certain modifications over the disclosure in Fig. 1.

Fig. 6 is a transverse sectional view, similar to Fig. 2, of a knocked-down or folded blank of Fig. 5 as shipped to the user.

Fig. 7 is a perspective view illustrating the half blank of Fig. 5 in erected position.

Fig. 8 is a longitudinal sectional view through the erected carton of Fig. 7 as seen on line 8—8 on said Fig. 8.

Fig. 9 is an extended plan view of a half blank showing another modification in the blank of Fig. 1, forming a resulting modified carton.

Fig. 10 is a transverse sectional view, similar to Fig. 2, of the knocked-down or folded blank of Fig. 9 as shipped to the user.

Fig. 11 is a perspective view of an erected carton from the portion of the blank illustrated in Fig. 9.

Fig. 12 is a longitudinal sectional view through the erected carton portion of Fig. 11 taken on line 12—12 on said Fig. 11.

Fig. 13 is a horizontal sectional view through the portion of the carton illustrated in Fig. 11 and taken on line 13—13 on said Fig. 11.

Fig. 14 is an extended plan view of a half blank, such as shown in Fig. 5, modified to the extent of having integral with the carton or box blank the blank to form an integral cover or lid.

Fig. 15 is a transverse sectional view, similar to Fig. 6 through a full blank of Fig. 14 illustrating the same in its folded or knocked-down condition as shipped to the user for erection by him.

Fig. 16 is a perspective view of an erected car-

ton with its lid or cover in an open position and erected from the portion of the blank of Fig. 14.

Fig. 17 is a longitudinal sectional view through the portion of the carton illustrated in Fig. 16 with its lid or cover in a closed position and as seen from line 17—17 on said Fig. 16.

Fig. 18 is a horizontal sectional view through the portion of the carton illustrated in Fig. 16 and taken on line 18—18 on said Fig. 16.

Fig. 19 is an extended plan view of a blank for forming a lid similar to the lid illustrated in Fig. 16 but separate from the box or carton itself.

Fig. 20 is a transverse sectional view through the knock down lid formed from the blank of Fig. 19 and illustrating said blank in the condition it is when shipped to the user.

Fig. 21 is a perspective view of a portion of a carton formed from the blank of Fig. 5 and having attached thereto the lid or cover formed from the blank of Fig. 19.

Fig. 22 is a longitudinal sectional view through the lid or cover of Fig. 21 as seen from line 22—22 on said Fig. 21.

Fig. 23 is an extended plan view of a half blank for forming a slip lid or cover that may be telescoped on to the box or carton formed from either of the blanks of Fig. 1, 5 or 9.

Fig. 24 is a transverse sectional view, similar to Fig. 2, of the blank of Fig. 23 in its flattened or knocked-down position and in the condition thereof as shipped to the user.

Fig. 25 is a perspective sectional view of an erected carton having mounted thereon the erected lid or cover set up from the blank of Fig. 23.

Fig. 26 is a longitudinal sectional view through the portion of the erected lid or cover of Fig. 25 as seen from lines 26—26 on said Fig. 25.

Fig. 27 is an extended plan view of a blank for forming a box or carton. From the upper end of each side wall projects a portion of the cover or lid thereof.

Fig. 28 is a transverse sectional view, similar to Fig. 2, of the folded blank of Fig. 27 in the condition it is shipped to the user.

Fig. 29 is a perspective view of the erected carton set up from the blank of Fig. 27 with the lid or cover portions in open positions.

Fig. 30 is a longitudinal sectional view through the portion of the carton of Fig. 29 assuming the lid or cover portions thereof in a closed position with said section taken on line 30—30 on said Fig. 29.

Fig. 31 is an extended plan view of a half blank similar to Fig. 27 showing however a minor modification.

Fig. 32 is a transverse sectional view through the blank of Fig. 31 showing said blank in its knocked down position as shipped to the user.

Fig. 33 is a perspective view of an erected carton formed from the half blank of Fig. 31 and showing the lid or cover portions for the carton in open positions.

Fig. 34 is a longitudinal sectional view through the portion of the erected carton in Fig. 33 with the lid or cover portions in a closed position with said section taken on line 34—34 on said Fig. 33.

Fig. 35 is an extended plan view of a half blank similar to that illustrated in Fig. 5 showing a slight modification in the end wall construction.

Fig. 36 is a transverse sectional view through the blank of Fig. 35 illustrating the same in its

knocked-down or folded position as shipped to the user.

Fig. 37 is a perspective view of an erected carton formed from the blank portion of Fig. 35.

Fig. 38 is a longitudinal sectional view through the portion of the carton illustrated in Fig. 37 as seen from line 38—38 on said Fig. 37.

Fig. 39 is a longitudinal sectional view through the erected carton portion of Fig. 41 taken through a plane laterally of that of Fig. 38 on line 39—39 on Fig. 37.

Fig. 40 is an extended plan view of a half blank of a lid or cover similar to Fig. 19 showing a modification therein and including means for securing or attaching the cover or lid to the box proper.

Fig. 41 is a perspective view of a set up carton having attached thereto the lid or cover of Fig. 40.

Fig. 42 is a fragmentary vertical sectional view through the carton of Fig. 41 taken on line 42—42 on said Fig. 41.

Throughout the several views of the drawings similar reference characters are employed to denote the same or similar parts.

It should be noted that the various modifications illustrated in the drawings and above briefly described are based on the blank illustrated in Fig. 1, said modification merely adding to or subtracting from the basic elements of the blank of Fig. 1. As noted above similar reference characters will be used to designate common elements and panels in the modifications with their bases in Fig. 1 except as were specifically otherwise indicated.

The underlying thought of the present invention is to provide a carton or box of the foldable variety that can be shipped to the user in a knocked-down condition and can readily be set up for use and which carton or box will receive and retain in position insulating or filler material. As noted above it is proposed to insulate the contents of the box or carton against the surrounding atmosphere, heat, cold and humidity to insulate the contents of the carton or box against breakage by shocks or jolts and to arrange articles relative the box or carton for proper shipment and display therein whether said articles are plural in number and differ in physical dimensions or whether said articles are single or plural in number and due to their cross sectional variance are of non uniform contour. Various specific uses of the carton or box will be made as the specific description of the modifications proceed.

Specifically, and referring to the drawing particularly Figs. 1 to 4 inclusive, the blank and the carton there shown comprises a panel 45 that forms the base of the carton and bounded by score or fold line 46, 47, 48 and 49. As is customary the score or fold lines 47 and 49, being the longer of the bounding edges of the panel 45, will be referred to as sides while the score or fold lines 46 and 48 being the shorter, will be referred to as ends. The panel 45 has integrally hingedly connected to its sides, respectively, through the score or fold lines 47 and 49 similar extensions 50 and 51 which form in the erected carton the side walls and since they are substantially identical it is deemed sufficient if but one of them be described in detail.

Accordingly, extension 51 is subdivided longitudinally with parallel score lines 52, 53, 54 and 55 into a plurality of parallel panels 56, 57, 58, 59 and 60 located between the score or fold line 49 and outer edge of the extension 51. In the

erected carton the panel 56 forms the side wall outer wall member and has its ends defined by score or fold lines 61 and 62 which are in substantial alignment with end score or fold lines 46 and 48 and the width of said panel 56 determines the height of the side walls. The panel 57 is of a length substantially equal to the length of the panel 56 and has its ends defined by cut lines 63 and 64 which are in substantial alignment with the score or fold lines 61 and 62. The panel 58 in the erected carton forms the side wall inner wall member and it is of a length substantially equal to the length of the panels 56 and 57 having its end defined by score or fold lines 65 and 66 in alignment with the cut lines 63 and 64. The height of the panel 58, or the side wall inner wall member, is less than that of panel 56, or the side wall outer wall member, whereby its lower edge is spaced above the carton bottom panel 45 for a purpose that will later be made clear. The panel 59 in the erected carton forms the side wall bottom wall member and is of a width substantially equal to the width of the side wall top wall member or panel 57. The ends of the panel 59 are defined by cut lines 67 and 68 which slightly taper so that the outer sides of the panel 59 are shorter than the inner side thereof. The panel 60 constitutes a fastening member or glue flap for which purpose it is provided with adhesive 69, shown with said adhesive below the panel as illustrated in Fig. 1.

The side wall inner wall member or panel 58 is provided near its outer corners with elongated apertures 70 and 71 which cooperate with end wall locking tabs, as will later be pointed out, in locking the walls in their erected position. In addition the said side wall inner wall member or panel 58 has integrally hingedly connected therewith through its ends score or fold lines 65 and 66, respectively, tucking flaps 72 and 73. The said tucking flaps 72 and 73 are respectively provided with a score or fold line 74 and 75 which are in substantial alignment with and extensions of the score or fold line 68 and the said score or fold lines 74 and 75, respectively, integrally, hingedly, connected with their respective tucking flaps 72 and 73, a spacer flap 76 and 77.

The carton bottom panel 45 has integrally hingedly connected therewith through the end score or fold lines 46 and 48 extensions 78 and 79 which are substantially identical in construction and respectively form an end wall for the carton and it is deemed sufficient if but one of them be described in detail.

Accordingly, the extension 78 is provided with a plurality of score or fold lines 80, 81 and 82 providing in the said extension parallel panels 83, 84, 85 and 86 located between the score or fold line 46 and the end of the extension 78. In the erected carton the panel 83 forms the end wall outer wall member and has its ends defined by score or fold lines 87 and 88. The panel 83 is of substantially the same width as the side wall outer wall member or panel 56 and constitutes the height of the carton. In the erected carton the panel 85 constitutes the end wall inner wall member and has its ends in the main defined by score or fold lines 89 and 90 which are inwardly spaced from the end wall outer wall member or panel 83 thereby resulting in a shorter panel since this end wall inner wall member or panel 85 is positioned between the side wall inner wall members or panels 58. The panel 84, between panels 83 and 85, in the erected carton forms the end wall top wall member and has its ends contoured

or biased as at 91 and 92 which serves the dual purpose of ornamentation in the erected carton and the connecting of the shorter panel 85 with the longer panel 83. The height of the end wall 5 inner wall member or panel 85 is less than the height of the end wall outer wall member or panel 83 wherefor the lower end of the end wall inner wall member or panel 85 is upwardly spaced from the carton main or bottom panel 45. The remaining panel 86 of the extension 78 is a spacer panel for maintaining lower end of the end wall inner wall member or panel 85 from the end wall outer wall member or panel 83 so that said end wall members are parallel to one another and 10 maintained in this relation after assembly.

The end walls outer wall members or panels 83 have integrally, hingedly, connected thereto through the score or fold lines 87 and 88 a corner piece 93 each of which has a second edge thereof 20 integrally hingedly, connected to the adjacent end of the side wall outer wall member panel through the score or fold lines 61 and 62. Each of said corner pieces is provided with a diagonal score or fold line 94 whereby the said corner pieces may be folded on themselves and then disposed transversely of the carton main or bottom panel 45 as will later be made clear. The end wall inner wall members or panels 85 each has integrally, hingedly, connected to its ends, respectively, through the score or fold lines 89 and 90 25 a spacer tab 95 and 96 adapted, in the erected carton, to space the vertical edges of the said end wall inner end wall member from the outer wall member or panel 83. The end wall inner wall member or panel 85, in addition has projecting, respectively, from its opposite ends a tab 97 and 98, which may be termed locking tabs adapted to enter the elongated apertures 70 and 71 of the 30 said wall inner wall member or panel 58 for locking the walls in their erected positions.

In practice and after the blank has been cut and scored as just described adhesive 69 is applied to the undersurface of each of the fastening or glue panels 60 whereupon the said panels 60 are 35 folded on the score or fold lines 55 onto the side walls bottom wall members or panels 59, or the said panels 60 are first folded on the score or fold lines 55 and then the adhesive 69 applied to the now exposed surface of said panels 60 whereupon the extensions are folded on the score or fold lines 52 to bring the glue flaps 60 with their adhesive 69 into engagement with the side walls outer wall members or panels 56 and pressure is then applied to effect the adhesion of these parts to one 40 another. The blank is then in the position illustrated by the upper part of Fig. 1 and as further illustrated in cross section in Fig. 2 and it is in this position that the blank is shipped to the user for subsequent erection and filling.

The user upon desiring to erect the carton in order to place therein merchandise raises the side walls from their folded knocked-down position to be normal to the carton main or bottom panel 45. This results in the said side walls being in the 45 positions illustrated in Fig. 3 with the said side walls inner and outer wall members 56 and 58 spaced from one another having the top wall member 57, joining the tops or the upper ends of the said inner and outer side wall members to one another and with the bottom wall member 59 joining the lower end of the inner wall member 58 to the outer wall member 56 but at a point 50 upwardly of the lower end of the outer wall member and thereby providing a space between the 55 said side walls bottom wall members and the 60 said side walls top wall members.

carton main or bottom panel 45. This space is indicated at 98 in Fig. 3 and is occupied by a filler 100. The filler 100 may be formed of insulating material which can act as a platform or as material that will retard the passage therethrough of heat and cold. The said insulation-filler 100 is an area substantially equal to the area of the carton main or bottom panel 45. After the placement of the insulation-filler material 100 the tucking flaps 72 and 73 at opposite ends of the side walls inner wall members 58 are folded to be disposed transversely of the insulation-filler 100 whereupon the spacer flaps 76 and 77, respectively carried by the tucking flap 72 and 73, are folded to be parallel with the insulation-filler 100 all as clearly illustrated in Fig. 3.

The corner pieces or "bellows corners" 93 are now respectively, folded on their diagonal score or fold lines 94 and are further folded to be transversely of the carton main or bottom panel 45 and which folding of the corner pieces automatically raises or the folding of the corner pieces 93 is automatically effected by the raising of the end wall extensions 78 and 79 to be upstanding each as a unit, to the carton base or bottom panel 45. The said extensions are respectively folded inwardly on their score or fold lines to dispose the end wall top wall panels 84, at the top of the end walls outer wall members 83, to be parallel with the main or bottom panel whereupon the end walls inner wall members 85 are folded to be disposed downwardly of the end walls top wall members 84 and to be parallel with the said end walls outer wall member. Previous to this folding of the end walls inner wall members the spacing flaps 95 and 96 at the ends thereof are folded to be normal to the end walls inner wall members and to automatically space the vertical edges of the end walls inner wall members from the outer walls members. The previous folding of the spacer flaps 86 to be normal to the end walls inner wall members 85 automatically disposes them on the upper surface of the insulation-filler 100 between the end walls inner wall members and the end walls outer wall members. The walls are locked in their erected positions upon the snapping or insertion of the end walls inner wall members locking lugs 97 and 98 into the side walls inner wall members locking apertures 70 and 71 which operation automatically takes place upon the final positioning of the end wall members.

From the foregoing it will be noted that the box or carton is provided with an insulated or built up bottom which extends throughout the area of the carton and beneath the spaced apart side and end walls; the disposal of the insulation and filler beneath the end wall is clearly illustrated in Fig. 4. It is contemplated and as will later be made clear that the side walls and the end walls may be provided throughout their length with insulation or filler material similar in all respects to the bottom insulation-filler material 100. This insulation-filler may be made of lengths equal to the length of the carton side walls outer wall members and with the end walls lengths of insulation filler shorter than the width of the carton by an amount occupied by the material in the two side walls or of a length substantially equal to the length of the end walls inner wall member, or any other method or means of insulating the said side and end walls may be employed, as will later appear.

It may be desirable that the bottom or base insulation filler material 100 not cover the en-

5 tire carton main or bottom panel 45 but only cover such an area as between the side walls outer wall members and the end walls inner wall members and such a construction is illustrated in Figs. 5 to 8 inclusive. In this case the carton blank has its end walls forming extensions 78 and 79 modified to the extent of making the end wall inner wall member or panel 85' of a height equal to the height of the end wall inner wall member and eliminating from the said end wall extension 78 and 79 the spacer flap 86. Otherwise the blanks are substantially identical and are formed and shipped to the user in the same manner as the blank disclosed in Fig. 1 and above described.

Upon assembling or erecting the blank of Fig. 5 the same steps are followed except that in the final positioning of the end walls inner wall members 85' the lower ends of said end walls inner wall members are disposed behind the end 10 101 of the insulation filler 100' as illustrated in Fig. 8. From this it will be seen that the insulation-filler 100' extends entirely across the carton main or bottom panel 45 to underlie the side walls as illustrated in Fig. 7 while the said insulation filler 100' extends only up to the end walls inner wall members as illustrated in Fig. 8.

Instead of having the base or bottom insulation-filler 100 arranged as in Figs. 3 or 4 or as in Figs. 7 and 8 it may be desirable to have the said insulation-filler disposed beneath the carton or box end walls but merely between the side walls inner wall members. This construction is illustrated in Figs. 9, 10, 11, 12 and 13, and necessitates the modifying of the blank of Fig. 1 principally to the extent of making the height of the panels or inner wall members 58 the same as to the height of the panels or outside wall members 56. This construction may be further modified by the elimination of the side walls bottom wall members 59 and making the panels thereof as the fastening or glue flaps 60 which would then be integrally hinged to the side walls inner wall members or panels 58 through the score or fold line 54. This glue flap 60 instead of being attached to the side wall outer wall member or panel 56 would be attached directly to the carton main or bottom panel 45.

50 The user would erect the knocked-down or folded blank of Fig. 9 in the same manner as the erection of the blank of Fig. 1. The resulting carton however would have the insulation-filler 100" extending transversely of the box or carton only between the side walls inner wall members 58, as illustrated in Fig. 11, while the said insulation-filler 100" would extend completely under the carton end walls as illustrated in Fig. 12.

60 As described above the side and end walls would be provided with insulation or filling material, corresponding to that on the carton main or bottom panel and that said wall insulation would be in the nature of strips. In Fig. 13 the insulation for the side and end walls is illustrated as integral with one another and comprising a base portion 102 adapted to be received, or enfolded in the end wall between the end wall inner and outer wall members 58 and 56. Projecting from the ends of the wall insulation-filler base 102 are arms 103 and 104 which are disposed in the side walls between the said side walls inner and outer wall members 56 and 58. It is contemplated that the insulation-filler arms 103 and 104 will be formed to a length substantially equal to one half of the length of the carton or box and that the

said insulation will be introduced into the side walls from the opposite ends thereof. In other words the walls insulation would be in the form of a U-shaped unit consisting of a base 102 and arms 103 and 104 from the opposite ends of the base 102.

In order however to utilize U-shaped walls insulation units the side wall inner wall members will have to be shorter than the outer wall members and this construction is illustrated in the modification of Fig. 9 wherein the score or fold line 65 for the end of the side wall inner wall member panel 58' is shown as inwardly spaced from the score or fold line 61 that defines the end of side wall outer wall member or panel 58. The inward spacing of the score or fold line 65 in Fig. 9 is substantially equal to the width of the end wall top wall member which determines the depth or thickness of said end wall. It will further be understood that the walls insulation-filler units, if employed, with the construction of Figs. 9 to 12, inclusive, will have the lower end of its base 102 relieved to permit the insertion therebeneath of the bottom insulation-filler 100' while the arms 103 and 104 will be of a height substantially equal to the height of the carton side walls, and should the said wall insulation-filler unit be employed with the modification of Figs. 5 to 8, inclusive, the base 102 of the insulation unit would be of a height substantially equal to the height of the end walls while the arms 103 and 104 would have their lower ends relieved to permit the insertion therebeneath of the bottom insulation-filler 100'. It is of course understood that with the modification of Figs. 1 to 4, inclusive the height of the wall insulation units base 102 and arms 103 would be equal to the height of the end walls and side walls above the bottom insulation filler 100.

The box or carton formed of either of the modifications heretofore described would be supplied with a lid or cover which would likewise be provided with insulation or filler material. This lid or cover may be of the separable type and telescoped onto the box or carton or it may be formed integral with one of the box or carton side walls, or the lid or cover may be hingedly attached to one of said side walls although separably formed, or the lid or cover may be divided and each portion of the divided lid or cover, respectively carried by one of the carton or box side walls. There is illustrated in this application an example of each of the foregoing types or kinds of lid or covers that disclosed in Figs. 14 to 18, inclusive, illustrating a lid or cover integral hingedly connected with one of the carton side walls and formed from a single blank that includes the carton or box and its cover or lid.

As shown in Fig. 14 the blank of Fig. 1 is modified to the extent of providing the lid or cover forming portion between the score or fold line 52 and the side wall top wall member or panel 57 in the extensions 51' of the blank. This cover or lid forming portion is provided with a plurality of score or fold lines 105, 106, 107, 108, 109 and 110 the latter integrally hingedly connecting one of the side wall's top wall member or panel 57 with the lid or cover forming portion. The score or fold lines 105 to 110, inclusive form between the score or fold line 52 the said side wall member or panel 57 parallel panels, 111, 112, 113, 114, 115 and 116.

In the erected carton the panel 111 forms the lid or cover outer member and has projecting from its ends similar extensions and said panel

has each of its ends defined by a score or fold line 118 which is in substantial alignment with the bottom or main panel end score or fold line 46 and 48 and which score or fold line 118 integrally, hingedly, connects with the panel 111 a foldable flap 119 that is folded onto the panel to provide strength and a finished appearance to the end of the panel 111. The panel 112 in the erected carton provides a flange on the cover or lid and is adapted to be adhesively secured to the cover panel 111 and for which purpose the panel 111 may be supplied with adhesive 120. The length of the panel 112 is substantially equal to the length of the panel 111 between the score or fold lines 118, one of said ends being shown as a cut line 121.

After the blank has been cut and scored as above described the various score lines are broken, that is, the blank has the several panels individually raised on their score line whereupon the panels are allowed to fall back to their normal position. It is at this time that the adhesive is applied for the several panels, namely, along the outer edges of the cover outer panel 111, as indicated at 120 and 120' or glue flap 60 as indicated at 60. The blank upon further passing through the machine has the portion thereof beyond the score or fold line 105 folded to bring the panel 112 into engagement with the adhesive 120 whereupon the portion beyond the score or fold line 106 is reversely folded to bring the panel 113 on top of the panel 112. The portion of the blank beyond the score or fold line 107 is again reversely folded thereby bringing the panel 116 into engagement with the glue or adhesive 120' on the opposite side of the panel 111 and at the same time bringing the glue flap 60, with its adhesive 60, into engagement with the side wall outer wall member along a zone outwardly of

40 said main panel side score or fold line 49.

The blank is now in the position illustrated in Fig. 15 it being understood that the other side of the blank, as exemplified by the side wall extensions 50, having been folded and secured as 45 above described in connection with the blank of Fig. 1.

The user upon desiring to set up the box or carton erects the same in the same manner as above described in so far as the box proper is concerned. To form the lid the cover inner panel 114 is arranged to be parallel with the cover outer panel 111 and spaced therefrom by the panels 113 and 115. The said cover inner and outer panels are spaced from one another at their ends by tucking flaps 122 and 123, respectively, integrally, hingedly carried by the said panels 113 and 114 through score or fold lines 124 and 125 at the ends of said panels 112 and 113. It should be noted that the score or fold lines 124 and 125 are inwardly of the score or fold lines 118 of the cover outer panel a distance substantially equal to the width of the end walls top wall members 84. The cover inner and outer panels 114 and 111 are further spaced from one another by end tucking flaps 55 connected to cover inner panel by score or fold lines 129 and each longitudinally divided by a score or fold line 126 into panels 127 and 128, the former acting as a spacer panel and the latter as a tucking flap. To finish the end of the cover the said cover outer panel 111 has its flap 119 folded on score or fold line 118 to lie against the said cover outer panel 111 and it is against this infolded flap that the tucking flap 128 of the cover inner panel engages.

75 The portions of the cover outer panel that pro-

ject beyond the ends of the cover inner panel 114 act as flanges at the ends of the said cover as do the overlapped and glued portions or panels 116 and 112 for the sides of the cover. In other words the cover has a peripheral flange entirely there around with a central depending portion which is spaced from the cover outer panel and which depending portion fits within the spaced inner side and end wall members. The said spaced portion of said cover is adapted to receive suitable insulation or filler material 130 which may be of any suitable or desirable characteristics.

One of the uses to which the package of the blank of Fig. 14 and set up as in Fig. 16 would be put is a cigar box or humidor. In using the package as a cigar box the bottom or main panel 45 would support the filler insulation material 100 while the hollow side and end walls would enclose filler-insulation material either in strips or utilizing the substantially U-shaped filler of Fig. 13 and including the base 102 and arms 103 and 104. In this case the material 130 carried by the lid or cover may conveniently take the form of absorbing material for carrying a humidifying agent such as water. To permit the humidified air to escape from the said material 130, the lid or cover inner panel 114 is illustrated as provided with a plurality of apertures 131. It is of course understood that should the package be utilized for some other purpose, such as a package for frozen foods, the apertures 131 may be omitted and the material 130 made as insulating material to prevent transfer of heat or cold into or from the package. In this last instance, namely, as a frozen food package, the material 130 may take the form of compressed carbon dioxide or "Dry Ice."

In the event that the package is utilized as a cigar container or cigar box for housing either 25 of 50 cigars, as is the usual practice, and since the said cigars are placed in either 2 or 4 rows and thereby having an unequal number of cigars in each row, use may be made of an additional filler in the form of a sheet of card or paper board 132 having an over-all area substantially equal to the area between the side walls inner wall members 58 and end walls inner wall members 85 with one end of said filler 132 creased or scored to fold into a box at one end thereof and which box is illustrated in Figs. 16, 17 and 18. As there shown the said box comprises upstanding portions 133 and 134 joined at their upper ends by a horizontal portion 135. In order to anchor the piece 132 in position it is provided with a flange 136 extending from the upstanding portion 134 which is adapted to be inserted behind an end of the insulation-filler or shown in Fig. 17 or may underlie the end wall inner wall member 85 and its spacing flap 86 if the form of Fig. 1 or Fig. 5 is employed.

The disclosure in Figs. 14 to 18, inclusive, shows the lid or cover integral with the box proper or carton and formed from the same blank while in Figs. 19 to 22 inclusive, there is illustrated a separate lid or cover for attachment to one of the modifications illustrated in Figs. 1 to 13, inclusive. As disclosed in Fig. 19 the separate lid or cover comprises a blank longitudinally scored to provide fold lines 137, 138, 139, 140, 141 and 142 to provide panels 143, 144, 145, 146, 147, 148 and 149. The said panels 143 to 148 inclusive are substantially identical with the panels 111 to 116 inclusive with the added panel 148 which acts as a spacer panel as well as a glue flap.

The ends of the panels 143 to 148 inclusive, are defined in the same manner as the ends of the above mentioned panels of the blank of Fig. 14, with said cover or lid outer panel provided with the score or fold line 143 for connecting thereto the in-folding flap 119. The cover or lid inner panel 147 has connected thereto through the score or fold line 129 the closing flap 127 and tucking flap 128 which are integrally hinged, connected to one another by the score or fold line 126. The side spacing panels 146 and 148 have each connected therewith the spacing flaps 122 and 123 through score or fold lines 124 and 125.

The cover or lid of the blank of Fig. 19 is provided with adhesive 150 on the under face of the panel 143 as illustrated in Fig. 19 while the cover or lid outer panel 149 is provided along its longitudinal sides and inwardly of the score or fold lines 138 and 139 with adhesive 151 and 152. The blank of Fig. 19 is folded as illustrated in Fig. 20 which consists in folding the panel 143 and 148 on the score or fold line 138 to thereby bring the panel 144 into engagement with the adhesive 151 and expose the adhesive 150 on the panel 143. The portion of the blank on the other side of the cover or lid outer panel 149 is folded on the score or fold line 139 to bring the panel 145 into engagement with the adhesive 152. A reverse fold is then effected on the score or fold line 140 bringing the panel 146 on top of the panel 45 whereupon the blank is again reversely folded on the score or fold line 141 thereby bringing the combined spacer and glue flap panel 148 into engagement with the previously exposed adhesive of the panel 143. Suitable pressure is applied to assure the adhesive of the various panels to one another that has adhesive between them. The blank as mentioned above is now in the position of Fig. 20 and it is in this position that the blank may be shipped to the user for subsequent use or applied to one of the cartons of Figs. 1 to 13 inclusive.

The lid or cover may be set up as illustrated in Fig. 21 which merely means the swinging of the cover or lid inner panel 147 to be parallel with the outer panel 149 whereupon in-folding flaps 119 are folded onto the underside of the said cover or lid outer panel 149 and the spacing flaps 122 and 123 folded to be transversely of the cover and the closure flaps 127 secured in position through the inwardly tucking of the tucking flaps 128.

By this construction there is provided a cover having a peripheral flange similar to that illustrated and described in connection with Fig. 16 and one of said flanges may be employed for the securing of the said cover or lid to the finished carton as clearly illustrated in Fig. 21. As illustrated in said Fig. 21 use is made of a connecting member, preferably of flexible material and located exteriorly of the lid or cover and the carton, and which member is indicated in the drawings by the reference numeral 153. A similar connecting member or hinge 154 may be applied to the flange along the inner side of the cover or lid flange and to the top wall member or panel 57 of the erected carton. The operation of the lid or cover of Fig. 19 is substantially the same as that of Fig. 14 and above described.

The modification illustrated in Figs. 23 to 26 inclusive is for a separable slip-type of lid or cover for use with either one of the boxes or cartons illustrated in Figs. 1 to 13 inclusive. The

lid or cover however is provided with thickened side walls for a portion only of their height which engages the top wall member of the carton side walls.

The blank as illustrated in Fig. 23 for forming the said cover or lid has a main panel 155 with its opposite side edges defined by a score or fold line 156 and its opposite end edges defined by a score or fold line 157. The score or fold lines 156 each hingedly connect to the bottom panel 155 an extension 158 which are substantially identical with one another in construction while each end score or fold line 157 connects to the main panel 155 an extension 159, which are again substantially identical in construction and 15 operation.

Each side wall extension 158 is longitudinally subdivided by score or fold lines 160, 161, 162, 163 and 164 to form therein between the score or fold line 156 and its end a plurality of parallel panels 165, 166, 167, 168 and 169 and 170. The ends of each panel 165 and 166 is respectively defined by a score or fold line 171 and 172 which are in alignment with one another and with the main panel end scores 157. The panel 166 has 25 connected to its ends through the score or fold lines 172 tucking flaps 173.

Each of the end wall extensions 159 is subdivided by score or fold lines 174 and 175 thereby providing panels 176, 177, 178 between the main panel score or fold line 157 and the end of said extensions 159. The ends of the panels 176 are each defined by a score or fold line 179 and 180 which hingedly connects thereto corner pieces 181 with said corner pieces 181 likewise being integrally, hingedly, connected through the score or fold lines 171 to the panels 165. Each of the corner pieces 181 forms, what is known as a "bellows corner" and for which purpose they are each provided with a diagonal score or fold line 182. The panel 177 in each extension 159 has a portion thereof of less length than the remaining portion thereby providing shoulders 183 and 184. Each panel 177 is further provided inwardly thereof from the corner of the shoulder 183 and 184 with relatively short converging cuts 185 and 186 thereby placing the shoulders at ends of locking lugs as will later be made clear.

In the erected lid or cover as formed from the blank of Fig. 23 the panel 165 forms an outer wall member while the panels 166 and 168 form an inner wall member offset by the panel 167 which forms a shoulder. The combined height of the inner wall member panels 166 and 168 is less than the height of the panel 165 thereby providing a space between the inner ends of said lid or cover side walls inner wall member and the main panel 155.

The blank of Fig. 23 is shipped to the user in a knocked-down position such as illustrated in Fig. 24 and to effect this the blank of Fig. 23 after being cut and scored has the panels 169 and 170 folded on the score or fold line 163 thereby exposing the undersurface of the panel 170 which becomes a glue flap and when so exposed applying adhesive 187 thereto whereupon the panels are folded on the score or fold line 160 to bring the adhesive 187 into contact with the panel 165 through a zone upwardly spaced from score or fold line 156 an amount equal to the 70 difference in heights of the lid or cover outer wall member and inner wall member.

The user upon desiring to set up the lid or cover follows substantially the same steps as above described in connection with setting up 75

the carton of the blank of Fig. 1. The set up lid or cover will have the cross section as illustrated in Fig. 25 and each end wall has its inner wall member shorter portion between the side walls inner wall members portions or panels 168 and its longer portion between the side walls inner wall members portions or panels 166. It is at this time that the shoulders or locking lugs 183 and 184 are disposed behind the side wall shoulders as provided by the inner wall member connecting panel 167. In the final assembly of the slip cover or lid the panel 178 acts as a creeper flange and lies on the filler-insulation 100", and at the same time this panel or flange 178 holds the ends of said insulation-filler 100" at the ends thereof against the lid or cover main panel 155.

It is believed that the operation of the internally shouldered lid or cover is obvious from the disclosure in Figure 25 and that the portion of the side walls outwardly of the shoulder panel 167 telescopically receive or slip onto the walls of the carton or box being covered thereby.

Instead of the panel 178 being of a comparatively short length as illustrated in Figs. 23 and 26 to act as a creeper flange the said flange 178 may be formed as a panel 188 illustrated in phantom lines in Fig. 23 and may be of a size to fit within the inner wall members of the cover or lid. By this construction the insulation-filler material 100" is completely covered and there is exposed to the observer the outer or right side of the board or material from which the cover or lid is formed. Furthermore by this construction any suitable or desirable printing may be done in the blank prior to its assembly and which will be exposed after assembly.

The modification illustrated in Figs. 27 to 30, inclusive, shows the carton having an integral lid or cover substantially centrally divided thereby providing a half cover integral with each side wall. The said figures likewise illustrate one of said half covers as having a flange longitudinally of its free edge to overlap the adjacent edge of the other half of the cover. The blank for forming the said carton is the blank of Fig. 1 modified as in Fig. 14 with the cover panels substantially identical except of but half the width and located on each side of the carton side wall panels.

Specifically, the blank of Fig. 27 has the side wall extension 51" formed between its score or fold line 52 and the side wall top wall panel 57 a portion provided with a plurality of score or fold lines 189, 190, 191, 192, 193, and 194 forming panels 195, 196, 197, 198, 199 and 200 which are substantially identical with the panels 111 to 116, respectively, of Fig. 14 except that the panels 195 and 198 are considerably narrower than the panels 111 and 114. In the extension 50" in Fig. 27 a portion is provided having substantially the same score or fold lines as the corresponding portion of extension 51" except that the panel 196 is omitted and the panel 197 is connected directly with the panel 195 through the score or fold line 189. A further distinction exists between the extension 50" and 51" in that the panel 195 of extension 50" is narrower by the width of the panel 196 than the panel 195 of the extension 51".

The ends of the panels 195 to 200 inclusive, are defined in the same manner as the corresponding panels 111 to 116, inclusive, of Fig. 14. Specifically, the panel 195 has its ends defined by score or fold lines 118 integrally, hingedly, connecting thereto the in-folding flap 119. The

panels 197 and 199 have their ends respectively defined by score or fold lines 124 and 125, in the same manner as panel 113 and 115 of Fig. 14, and said score or fold lines 124 and 125 integrally, hingedly, connected to said panels spacing flaps 122 and 123. The panel 193 similar to the panel 114 has its end defined score or fold lines 129 that hingedly connect thereto a flap longitudinally divided by the score or fold line 126 to provide closing flap 127 and tucking flap 128.

After the blank of Fig. 27 has been cut and scored as above described its various score or fold lines are broken in the same manner as above described in connection with the blank of Fig. 14 whereupon adhesive is applied to the several panels and the folding of said panels is made in the same manner as in the blank of Fig. 14 except that each of the extensions 50" and 51" are similarly treated and the various panels folded into contact with the adhesive so that a blank folded as disclosed in Fig. 28 results.

The user upon desiring to place merchandise within the carton of the blank of Fig. 27 sets up the knock down blank in the same manner as the knock down blank of Fig. 15 was set up with the blank extension 51" forming a half cover having a flange 291, see Fig. 29, projecting from its free end while the half cover of the extension 50" has no similar longitudinal central flange. Extending from both ends of the half covers are flanges which overlap the upper ends of the carton end walls as disclosed most clearly in Fig. 30.

The modification illustrated in Figs. 31 to 34 inclusive is substantially identical with the blank of Fig. 27 except that each of its extensions 50a and 51a are formed identically as the extension 50" of Fig. 27, that is each extension having the panels 195 of the same width and which is the width of panel 195 in extension 51" minus the width of the panel 196 and neither of said extensions 50a and 51a employing the flange forming panel 196.

The blank of Fig. 31 after being cut and scored is provided with the usual adhesive and the extension folded to provide the knock down carton illustrated in transverse cross section in Fig. 32. It will be noted that since neither half of the cover of the blank of Fig. 31 has a longitudinal extending overlapping flange the knock down carton in Fig. 32 requires no reverse folding.

The user upon desiring to set up the blank of Fig. 32 proceeds in the same manner as above described with a resulting carton as illustrated in Fig. 33, namely, the cover halves devoid of any overlapping flange. The blank of Fig. 31 differs from the blank of Fig. 14 and the blank of Fig. 1 to the extent that the end wall inner and outer wall members are of equal depth instead of one of said wall members being shorter than the other. In other words the end wall extension of Fig. 31 is formed as the end wall extension of Fig. 5 whereupon the said end wall inner wall member depends to the main or bottom panel 45 as illustrated in Fig. 34.

In each of the constructions heretofore described the carton side and end wall are disclosed as of hollow construction that is with the side walls each having spaced apart inner and outer wall members. In the modification illustrated in Figs. 35 to 39 inclusive the end wall is provided merely with double thickness, that is, inner and outer end wall members that contact one another on their inner faces, the side walls how-

5 10

ever are of the same construction as heretofore described. This modification consists in merely changing the end wall extensions 78 and 79 to the extent of eliminating therefrom the end wall top wall members or panels 84 and integrally hingedly connecting to the end walls outer wall panels or members 83 through the score or fold lines 88 the end walls inner wall member panels 85'. The said end walls inner wall members or panels 85', since they fit between the side walls inner walls members or panels are shorter than the said end walls outer wall members 83 by the width of the side walls top wall members or panels 57 as above described.

Projecting from the said end walls outer wall members 83, beyond the ends of the end walls inner wall members or panel 85', are flaps 292 and 293 which are adapted to be tucked beneath the side walls top wall members upon erection of the carton as clearly illustrated in Fig. 39. By this construction an additional means is provided for holding the side walls in erected positions.

The blank of Fig. 35 after being cut and scored 25 is glued or secured in the same manner as the blank of Fig. 1 and illustrated in cross section in Fig. 36.

The user upon desiring to set up the carton from the knocked-down blank of Fig. 36 does so in the same manner as above described with the additional function of inserting the tabs 292 and 293 beneath the side walls top wall members.

The separate lid and its attachment to a box or carton as illustrated in Figs. 19 to 21, requires 35 extraneous means, such as the hinge strips or members 153 and 154, in order to attach it to the carton or box. In the modification illustrated in Figs. 40, 41 and 42 the attaching means are integral with the lid and the carton. The blank of 40 Fig. 40 is substantially identical with the blank of Fig. 19 except that the flange forming panel 145' is provided with a cut to form a lug 204 which is substantially T shaped and has a stem portion 205 connected with the cover outer panel 149 through the score or fold line 139, and laterally projecting wing or lug portions 206 and 207. The said wing or lug portions 206 and 207 are separated from the stem portion 205 by score or fold lines 203 and 208.

The blank of Fig. 40 after having been cut and scored has the various scores broken as above described in connection with Fig. 14 whereupon adhesive is applied to said main panel 149 and the panel 143 whereupon the blank is folded to secure the parts, adhesively, to one another as illustrated in Fig. 20. The user upon desiring to set up the lid or cover of Fig. 40 merely swings the said cover panels 147 and 148 to be parallel to one another whereupon the flap 119 is folded 50 on the score or fold line 118 to be within the cover pocket and the said panels secured in their spaced apart relation by the spacing and tucking flaps 122, 123, 127 and 128. By this arrangement the cover or lid has downwardly projecting from it the T-shaped lugs 204.

The lid or cover of Fig. 40 is shown in Figs. 41 and 42 as applied to a carton made from the blank of Fig. 1. In order however to effect this attachment the blank of Fig. 1 is modified by providing in one of the side wall top wall members or panels 57 a slot or elongated perforation 210 for each hinge lug 204, one of which is clearly illustrated in Fig. 42. It will be understood that the elongated perforations or slots 210 are located 70 in the said side wall top wall member in accord-

ance with the location of the hinge lugs 204 projecting from the cover or lid. The carton blank of Fig. 1 is set up in the same manner as above described.

The user upon desiring to connect the lid or cover of Fig. 40 with the carton folds the laterally projecting wings or lugs 206 and 207 on its respective score or fold line 208 and 209 to lie on the hinge lug stem 205 and the parts are then inserted through the carton slots 210. Due to the springiness of the material from which the cover or lid is formed the ears or lugs 206 and 207 upon passing beneath the side wall top wall member 57 spring back to their original or normal position as seen in Fig. 42. The springing of the hinge ears or lugs 206 and 207 to their normal position is permitted by the interior hollowness of the said side wall.

It will be understood that the cover or lid of Fig. 40 when erected as in Fig. 41 can receive insulation, absorbing or other filler material to cooperate with similar material within the carton side and end walls and on the carton main or bottom panel all as above fully described.

It will be understood that by utilizing the hinge lug 204 in a hollow wall the lug itself moves within the wall oscillating on the said hinge ears or wings 206 and 207 without effecting any bend in the card or paper board material itself. By this construction the life of the hinge connection or the number of times the lid or cover may be opened or closed is indefinite without crystallizing or cracking of the material in either the carton or the lid or cover.

From the foregoing it should now be noted that there has been provided a box or carton particularly adapted to have integral therewith or releasably or permanently attached thereto a lid or cover or spaced apart insulation package that can be employed for frozen foods, a humidor or any other purpose where it is desired to retard loss of heat, cold, moisture or dryness within the package or carton. It will further be noted that the said packages may be readily supplied to users in a knocked-down condition thereby materially reducing shipping and storage space, and the incidental cost to shipping and storing, over set up boxes or packages that have been heretofore produced and employed for these purposes. It will further be noted that each of the foregoing cartons accomplishes the objects otherwise initially set forth.

What is claimed is:

1. In a carton part of the class described formed from a single blank of paper or card board material and comprising a main or bottom panel, articulated side and end walls each formed of an extension, respectively, from a side or end of the main or bottom panel and having an inner and an outer wall member, at least two opposed walls of said walls having its inner and outer wall members spaced from one another at least for a portion of their height and having said spaced members connected to one another by a top wall member, the said spaced inner and outer wall members having the ends thereof remote from the main or bottom panel disposed the same distance from the main or bottom panel, and said spaced inner wall members each having its other end upwardly spaced from said main or bottom panel and having a bottom wall member hingedly connected to the lower end thereof and a glue flap carried by each of said bottom wall members securing each of said inner wall members to its outer wall member but spaced therefrom to pro-

vide an appreciable space between said main or bottom panel and the ends of said opposed inner wall members, and a filler on said main or bottom panel of a thickness substantially equal to

5 the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members.

2. In a carton of the class described formed

15 from a single blank of paper or card board material and comprising a main or bottom panel, articulated side and end walls each formed of an extension, respectively, from a side or end of the main or bottom panel and having an inner and an outer wall member, at least two opposed of said walls having its inner and outer wall members spaced from one another at least for a portion of their height and having said spaced members connected to one another by a top wall member, the said spaced inner and outer wall members having the ends thereof remote from

20 the main or bottom panel disposed the same distance from the main or bottom panel, and said spaced inner wall members each having its other end upwardly spaced from said main or bottom panel and having a bottom wall member hingedly connected to the lower end thereof and a glue flap carried by each of said bottom wall members securing each of said inner wall members to its outer wall member but spaced therefrom to pro-

25 vide an appreciable space between said main or bottom panel and the ends of said opposed inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members,

30 and a cover or lid at the upper end of one wall hingedly connected thereto for movement toward and from a closing position.

3. In a carton part of the class described

35 formed from a single blank of paper and card board material and comprising a main or bottom panel, articulated side and end walls each formed of an extension, respectively, from a side or end of the main or bottom panel and having an inner and an outer wall member, at least two opposed of said walls having its inner and outer wall members spaced from one another at least for a portion of their height, and having said spaced

40 members connected to one another by a top wall member, the said spaced inner and outer wall members having the ends thereof remote from the main or bottom panel disposed the same distance from the main or bottom panel, and said spaced inner wall members each having its other end upwardly spaced from said main or bottom panel and having a bottom wall member hingedly connected to the lower end thereof and a glue flap carried by each of said bottom wall members securing each of said inner wall members to its outer wall member but spaced therefrom to pro-

45 vide an appreciable space between said main or bottom panel and the ends of said opposed inner

wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members, and a cover or lid at the upper end of one wall hingedly connected thereto for movement toward and from a closing position, comprising an outer panel of an area defined by the carton side and end walls outer wall members, and a panel depending from said first panel and of an area defined by the carton side and end walls inner wall members whereby the cover or lid has a spaced portion depending within the carton part walls.

4. In a carton part of the class described formed from a single blank comprising a main or bottom panel, articulated side and end walls respectively, formed from an extension from a side or end of the main or bottom panel and having an inner and an outer wall member, at least two opposed of said walls having its inner and outer wall members spaced from one another with their upper ends connected by a top wall member, said spaced inner wall members being of less width than their outer wall members whereby the lower ends of said spaced inner wall members are upwardly disposed from the bottom or main panel and having a bottom wall member hingedly connected to the lower end thereof and a glue flap carried by each of said bottom wall members securing each of said inner wall members to its outer wall member but spaced therefrom to provide an appreciable space between said main or bottom panel and the adjacent ends of said walls inner wall members a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members.

5. In a carton part of the class described formed from a single blank and comprising a main or bottom panel, articulated side and end walls respectively formed of an extension each from a side or end of the main panel, two opposed walls of said walls each having an outer wall member hingedly connected to the main or bottom panel, a top wall member, and an inner wall member, with said inner wall members each of less height than the outer wall member and with each of said inner wall members of less height having a bottom wall member hingedly connected to the lower end thereof and a glue flap carried by each of said bottom wall members securing each of said inner wall members to its outer wall member but spaced therefrom whereby the lower end of each of the inner wall members is upwardly spaced from the main or bottom panel, and said remaining two opposed walls each having an outer wall member hingedly connected to the bottom or main panel, a top wall member and an inner wall member, with said last named inner and outer wall members of similar width whereby said last named wall members extend to the main or bottom panel, means at the lower

ends of each inner wall member of the last named opposed walls for spacing it from its outer wall member, and a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members.

6. In a carton part of the class described formed from a single blank of card or paper board material comprising a main or bottom panel, articulated side and end walls respectively formed from an extension from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member but spaced therefrom whereby the lower ends of such inner wall members are upwardly spaced from the main or bottom panel to provide an appreciable space between said main or bottom panel and the adjacent ends of said inner wall members, and a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members.

7. In a carton part of the class described formed from a single blank of card or paper board material comprising a main or bottom panel, articulated side and end walls each formed from an extension respectively from a side or end of the main or bottom panel, each wall having an outer wall member integrally, hingedly connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member but spaced therefrom whereby the lower ends of such inner wall members are upwardly spaced from the main or bottom panel to provide an appreciable space between said main or bottom panel and the adjacent ends of said inner wall members a filler on said main or bottom panel of a thickness substantially equal to the space between said main or bottom panel and the upwardly spaced inner wall members and extending from one outer wall member of one of said two opposed walls to the outer wall member of the other of said walls and

laterally across the main or bottom panel between the remaining walls so as to provide insulation for the carton main or bottom panel, at least, for the portion thereof defined by the walls inner wall members, and means carried by the inner wall members locking the walls in erected positions.

8. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member but spaced therefrom whereby the lower ends of such inner wall members are upwardly spaced from the main or bottom panel to provide an appreciable space between said main or bottom panel and the adjacent ends of said inner wall members a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members, means carried by the inner wall members locking the walls in erected positions, and the remaining two opposed walls each having means at the lower ends of their inner wall members spacing them from their respective outer wall members.

9. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of

said walls and laterally across the main or bottom panel between the remaining walls so as to provide insulation for the carton main or bottom panel, at least, for the portion thereof defined by the walls inner wall members and a cover or lid at the upper end of one of said walls and hingedly connected thereto for oscillation from a closed to an open position.

10. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls and hingedly connected thereto for oscillation from a closed to an open position and formed from material in the blank between the carrying wall's outer wall member and top wall member.

11. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the

outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls and hingedly connected thereto for oscillation from a closed to an open position, comprising a first panel of an area included between the carton part wall's outer wall members, a second panel of an area included between the carton part wall's inner wall members and means connecting said lid or cover panels to one another whereby said lid or cover first panel forms a projecting flange around the lid or cover second panel.

12. In a carton part of the class described formed from a single blank of card or paper board material comprising a main or bottom panel, articulated side and end walls each formed from an extension respectively from a side or end of the main or bottom panel, each wall having an outer wall member integrally, hingedly connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls and hingedly connected thereto for oscillation from a closed to an open position, and formed from material in the blank between the carrying walls outer wall member and top wall member comprising a first panel of an area included between the carton part outer wall members, a second panel of an area included between the carton part inner wall members, and means connecting said lid or cover panels to one another whereby said lid or cover first panel forms a projecting flange around the lid or cover second panel.

13. In a carton part of the class described formed from a single blank of card or paper board material comprising a main or bottom panel, articulated side and end walls respectively formed from an extension from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall

member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a lid or cover portion carried by each of two opposed walls with said lid or cover portions, respectively, hingedly connected to its wall for oscillation toward and from a closed position and with said lid or cover portions together having an area co-extensive with the area of the carton as defined by its outer wall members.

14. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a lid or cover portion carried by each of two opposed walls with said lid or cover portions, respectively, hingedly, connected to its wall for oscillation toward and from a closed position and with said lid or cover portions together having an area co-extensive with the area of the carton as defined by its outer wall members, and with said lid or cover portions, respectively, formed from portions of said blank lying between its carrying wall outer wall member and top wall member.

15. In a carton part of the class described formed from a single blank of card or paper board material comprising a main or bottom panel, articulated side and end walls each formed from an extension respectively from a side or

end of the main or bottom panel, each wall having an outer wall member integrally hingedly connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a lid or cover portion carried by each of two opposed walls with said lid or cover portions respectively, hingedly, connected to its wall for oscillation toward and from a closed position and with said cover portions together having an area co-extensive with the area of the carton as defined by its outer wall member, each lid or cover portion having a first panel of an area of substantially one half of the total area of the lid or cover, a second panel of an area equal to substantially one half of the area of the carton part as defined by its inner wall members, and means for connecting the panels of each cover portion in spaced apart relation whereby when the cover portions are in closed positions their second panels are within the carton part.

16. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a lid or cover portion carried by each of two opposed walls with said lid or cover portions respectively, hingedly, connected to its wall for oscillation toward and from a closed position and with said cover portions together having an area co-extensive with the area of the carton as defined by its outer wall member, each lid or cover portion having a first panel of an area of substantially one half of the total area of the lid or cover, a second panel of an area equal to substantially one half of the area of the carton part as defined by its inner wall members, and means for connecting the panels of each cover portion in spaced apart relation whereby when the cover portions are in closed positions their second panels are within the carton part.

the remaining walls so as to provide insulation for the carton main or bottom panel, at least, for the portion thereof defined by the walls inner wall members and a lid or cover portion carried by each of two opposed walls, respectively formed from portions of said blank lying between its carrying wall outer wall member and top wall member and with said lid or cover portions, respectively, hingedly, connected, to its wall for oscillation toward and from a closed position and with said cover portions together having an area co-extensive with the area of the carton as defined by its outer wall member, each lid or cover portion having a first panel of an area of substantially one half of the total area of the lid or cover, a second panel of an area equal to substantially one half of the area of the carton part as defined by its inner wall members, and means for connecting the panels of each cover portion in spaced apart relation whereby when the cover portions are in closed position their second panels are within the carton part.

17. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls hingedly connected thereto for oscillation from a closed to an open position, including a cover or lid panel of an area substantially co-extensive with the area of the carton part as defined by the carton outer wall member, hinge lugs projecting from the said lid or cover panel, and one of said carton walls having slits therein to receive the lid or cover hinge lugs.

18. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending

from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls, hingedly connected thereto for oscillation from a closed to an open position, including a cover or lid panel of an area substantially co-extensive with the area of the carton part as defined by the carton outer wall member, hinge lugs projecting from the said lid or cover panel, one of said carton walls having slits therein to receive the lid or cover hinge lugs, and means integral with said hinge lugs for preventing inadvertent withdrawal thereof through the carton wall slits.

19. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls, formed from a second blank scored and folded to provide a lid or cover first panel of an area substantially co-extensive with the area of the carton part as defined by the carton part outer wall members, a lid or cover second panel of an area co-extensive with the area of the carton part as defined by the carton part inner wall members, spacing panels between the lid or cover first and second panels, flange forming panels between the spacing panels and the sides of the first panel adapted, when the lid or cover is closed, to engage the carton part top wall members with the said lid or carton part second panel within the carton part inner wall members, and hinge lugs projecting from one side of the lid or cover first panel, and slits in one of the carton part walls for receiving the hinge lugs.

said lid or cover panel, one of said carton walls having slits therein to receive the lid or cover hinge lugs, a second panel for said cover or lid carried by said first mentioned cover or lid panel and depending therefrom, said second cover or lid panel being of an area substantially co-extensive with the carton part area as defined by the inner wall members.

20. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls, formed from a second blank scored and folded to provide a lid or cover first panel of an area substantially co-extensive with the area of the carton part as defined by the carton part outer wall members, a lid or cover second panel of an area co-extensive with the area of the carton part as defined by the carton part inner wall members, spacing panels between the lid or cover first and second panels, flange forming panels between the spacing panels and the sides of the first panel adapted, when the lid or cover is closed, to engage the carton part top wall members with the said lid or carton part second panel within the carton part inner wall members, and hinge lugs projecting from one side of the lid or cover first panel, and slits in one of the carton part walls for receiving the hinge lugs.

21. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls, and hingedly connected thereto for oscillation from a closed to an open position, including a cover or lid panel of an area substantially co-extensive with the area of the carton part as defined by the carton outer wall member, hinge lugs projecting from the said lid or cover panel, one of said carton walls having slits therein to receive the lid or cover hinge lugs, and means integral with said hinge lugs for preventing inadvertent withdrawal thereof through the carton wall slits.

end thereof and a glue flap carried by each of said bottom wall members securing each of said wall members to its outer wall member but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members and a cover or lid at the upper end of one of said walls formed from a second blank scored and folded to provide a lid or cover first panel of an area substantially co-extensive with the area of the carton part as defined by the carton part outer wall members, a second lid or cover panel of an area co-extensive with the area of the carton part as defined by the carton part inner wall members, spacing panels between the lid or cover first and second panels, flange forming panels between the spacing panels and the sides of the first panel adapted, when the lid or cover is closed, to engage the carton part top wall members with the said lid or carton part second panel within the carton part inner wall members, hinge lugs projecting from one side of the lid or cover first panel, slits in one of the carton part walls for receiving the hinge lugs, and means carried by the hinge lugs for preventing inadvertent withdrawal of the hinge lugs from the carton wall slits.

22. In a carton part of the class described formed from a single blank of card or paper board material comprising a main or bottom panel, articulated side and end walls each formed from an extension respectively from a side or end of the main or bottom panel, each wall having an outer wall member integrally, hingedly, connected to the main or bottom panel, a top wall member at the upper end of the outer wall member and an inner wall member depending from the top wall member, at least two opposed of said inner wall members being of less width than its outer wall member with each of said inner wall members of less width having a bottom wall member hingedly connected to the lower end thereof and a glue flap carried by each of said bottom wall members securing each of said inner wall members to its outer wall member

but spaced therefrom whereby the lower ends of such inner wall members are upwardly spaced from the main or bottom panel to provide an appreciable space between said main or bottom panel and the adjacent ends of said inner wall members, a filler on said main or bottom panel of a thickness substantially equal to the space between said main or bottom panel and the upwardly spaced inner wall members and extending from one outer wall member of one of said two opposed walls to the outer wall member of the other of said walls and laterally across the main or bottom panel between the remaining walls so as to provide insulation for the carton main or bottom panel, at least, for the portion thereof defined by the walls inner wall members, and a cover or lid at the upper end of one of said walls formed from a second blank scored and folded to provide a lid or cover first panel of an area co-extensive with the area of the carton part as defined by the carton part outer wall members, a lid or cover second panel of an area co-extensive with the area of the carton part as defined by the carton part inner wall members, spacing panels between the lid or cover first and second panels, flange forming panels between the spacing panels and the sides of the first panel adapted, when the lid or cover is closed, to engage the carton part top wall members with the said lid or carton part second panel within the carton part inner wall members, hinge lugs projecting from one side of the lid or cover first panel, slits in one of the carton part walls for receiving the hinge lugs, said hinge lugs each having a stem of a width substantially equal to the length of the carton part wall slit, and projecting ears, bendable on to the hinge stem while being inserted through the hinge wall slits, and springable to positions beyond the ends of said slits to prevent withdrawal of the hinge lugs.
